Des. 175,817
Patented Oct. 11, 1955

175,817

PLASTIC SHEET MATERIAL

Russel Wright, New York, N. Y.

Application December 20, 1954, Serial No. 33,602

Term of patent 14 years

(Cl. D87—3)

Fig. I

Des. 175,817

PAGE 2

Fig. II

Fig. III

Figure I of the drawings is a plan view of one full repeating pattern and parts of all adjacent repeating patterns. Figure II is an additional plan view on a larger scale showing only one full repeating pattern. Figure III is an additional plan view on a still larger scale showing only a portion of one repeating pattern.

I claim:

The ornamental design for a plastic sheet material, substantially as shown.
